GRINDING MACHINE

Application filed May 27, 1930. Serial No. 456,205.

This invention relates to improvements in grinding machines and particularly to an improved structure for truing or redressing the active face of grinding wheels.

5 In the use of automatic production grinding machines use is made of a sizing control to hold successive work pieces to the same exact size. At the present time the working tolerance is extremely small being in many 10 cases less than a thousandth part of an inch. To produce work pieces on a production basis the mechanism must operate with an extreme nicety and the cutting face of the grinding wheel must be maintained at all times in its 15 best condition. Furthermore, the high production standard of the present day requires the retruing or redressing of the face of the grinding wheel be done in a minimum of time and in the most expeditious manner.

20 It is, therefore, one of the principal objects of the present invention to provide an improved mechanism for maintaining the sharp clean cutting face on a grinding wheel.

Another object of the invention is the provision of automatic means for automatically 25 retruing or redressing the active face of the grinding wheel in a minimum of time without disturbing the setting of the machine or interfering with the constant production 30 thereof.

Another object of the invention is the provision of an improved wheel diamonding or 35 retruing mechanism coupled in with the normal cycle of the machine so as to function at a predetermined point in the cycle thereof.

A further object of the invention is the provision of improved means capable of being adjusted to vary the cycle of operation 40 so that the surface of the grinding wheel may be retrued or redressed at the completion of each work piece, or after the completion of any definite number of work pieces.

Other objects and advantages of the present invention should be readily apparent by 45 reference to the following specification considered in conjunction with the accompanying drawings forming a part thereof, and it is to be understood that any modifications 50 may be made in the exact structural details without departing from or exceeding the

spirit of the invention, within the scope of the appended claims.

In the drawings:

Figure 1 is a front elevation of a grinding machine embodying the improvements of this 55 invention.

Figure 2 is a rear elevational view of the device shown in Figure 1.

Figure 3 is a sectional view taken on line 3—3 of Figure 2. 60

Figure 4 is a sectional view taken on line 4—4 of Figure 3.

Figure 5 is a sectional view taken on line 5—5 of Figure 3.

Figure 6 is a sectional view taken on line 6—6 of Figure 1.

Figure 7 is an enlarged view of the removable trip dog parts being shown in cross section and forming a detail of the invention.

Figure 8 is a longitudinal sectional view 70 through the trip mechanism, including the electric operating switch, and

Figure 9 is a diagrammatic view showing the hydraulic and electric circuits involved in the invention. 75

Throughout the several views of the drawings similar reference characters are employed to denote the same or similar parts.

For purposes of illustration the improved, novel truing mechanism has been shown as 80 applied to an internal grinder or whole generator. This machine may comprise a bed 10 having formed on its upper end in horizontally spaced planes the ways 11 and 12. Supported by the ways 11 is the grinding 85 wheelhead 13 having a motor 14 coupled with spindle 15 for rotating the small or internal grinding wheel 16 at the desired rate. The head 13 is adapted to be reciprocated longitudinally of the bed 10 on the ways 11 by 90 an hydraulic medium through a piston 17 having a piston rod 18 coupled therewith in any suitable or desirable manner. The piston 17 is contained in a cylinder 19 through which it reciprocates under the influence of the hydraulic medium. This hydraulic medium is contained in a tank or sump 20, from which it is drawn through a conduit 21 by a pump 22 being discharged from the pump through conduit 23. A con- 100

duit 24 conveys the medium from the conduit 23 to conduit 25 which is coupled through a reversing valve 26, where it is directed to one side or the other of piston 17, and as shown in Figure 9 the medium passes through conduit 27 to the right hand side of the piston. The hydraulic medium within in the cylinder 19 on the other side of the piston 17 is discharged through conduit 28 to the valve 26 where it is directed through conduit 29 to the main valve 30 for discharge through common discharge conduit 31 back to the tank or sump 20.

The valve 26 has extending from it a stem 32 coupled with a reversing lever 33, mounted exterior of a plate 34 on the front of the bed 10 for rocking movement through a shaft 35. The plate 36 of the wheelhead 13 is provided with a T-slot or the like 37 in which is adjustably secured trip dogs 38 and 39. The opposed abutting faces of the dogs 38 and 39 are on opposite sides of the lever 33 for engagement therewith, to effect the shifting or rocking of the lever thereby to effect a shifting of the valve 26 and a constant reverse longitudinal movement of the wheelhead 13 and grinding wheel 16. The dogs 38 and 39 are adjustable thereby to vary the length of stroke of the wheelhead 13 to permit the grinding wheel 16 to traverse the work throughout its entire length for breaking up grinding lines and the like thereon.

Supported by the bed 10 and guided by the guideways 12 for movement longitudinally of the bed toward and from the wheelhead 13 is a slide 40. The slide 40 is provided with a transverse dove-tailed guide 41 received in a similarly formed dove-tailed guideway 42 formed in the base of work head 43. The work head 43 supports a work rest blade 44 having an angular top 45 on which the work piece 46 is mounted for rotation. On one side of the work rest 44 is rotatably mounted a frictional driving and control member 47 for imparting rotation to, and controlling the rotation of the work piece 46. On the other side of the work rest 44 is rotatably mounted a pressure member 48 for holding the work piece 46 in frictional engagement with the wheel 47 to insure the proper contact between the wheel 47 and work.

The slide 40 and wheelhead 43 are adapted to be actuated longitudinally of the bed to an operating position adjacent the grinding wheel 16 and to a position remote from the said grinding wheel to permit a replacement of the work on the blade 44 at the completion of each work piece. This movement is imparted to the said parts by hydraulic pressure which passes from the pressure line 24 through a conduit 49 to a valve casing 50, enclosing a slide valve 51. The slide valve 51 directs the medium through either a conduit 52 or 53 coupled with opposite ends of a

cylinder 54 in which a piston 55 is located for reciprocation therethrough. As shown in Figure 9, the medium passes from the casing 50 through conduit 52 to the right hand side of piston 55 discharging the medium ahead of it through conduit 53 to the valve casing 50. The medium then passes from the valve casing 50 through a conduit 57 to the main valve 30 where it is directed to the common discharge line 31 for return to the tank or sump 20. The piston 55 has extending therefrom a piston rod 56 coupled with the slide 40, whereby the movement imparted to the piston 55 carries with it the said slide 40 and work head 43.

The valve 51 has extending from it a valve stem similar to the valve stem 32, which is coupled with a rock shaft 58, having keyed to its end, exterior to the plate 59, a shift lever 60. The shaft 58 is also pivotally coupled with a link 61 extending longitudinally of the bed along the front face thereof, and pivoted at its other end with a link 62. The lower end of the link 62 is pivoted to a block 63 and has protruding from it toward the work head 43 a pin or abutment adapted to be engaged by adjustable dogs 64 and 65. These dogs 64 and 65 are adjustably mounted in a T-slot 66 formed along the face of the slide 40.

Automatic means, not shown, for gaging the size of the work is employed for shifting the valve 51 in one direction at the completion of each grinding operation to effect a withdrawal of the work head from the operative position. During the withdrawal of the wheelhead, an automatic ejector 67 removes the work piece from the supporting blade 44 whereupon an unfinished work piece is automatically placed on the said support and a reverse adjustment of the valve 51 obtained to again return the work head to its operative position, whereupon the dog 65 engages link 62 to shift the valve 51 to a neutral position and stop further movement of work head 43. At this time the grinding wheel 16 is within the bore in the work piece and the work head 43 is actuated transversely of the plate 40 through a feeding mechanism, indicated diagrammatically in Figure 1 by the numeral 68, to feed the work piece into the grinding wheel and effect a stock removal therefrom. During this feeding movement, and in fact as long as the machine is in operation, the wheel head is constantly reciprocating through its guideways 11 to produce on the work piece to the proper desired finish. As soon as the work piece has been ground to the proper size the cyclic movement of the work head is repeated to replace said work piece with an unfinished one.

As was noted above, the active surface of the grinding wheel 16 may be retrued or redressed after the completion of the grinding operation on each piece, or this retruing or

redressing may occur after the completion of a certain number of pieces. To this end the wheel head 43 has mounted thereon a cylinder 70, containing for reciprocating movement therethrough, a piston 71. A piston rod 72 extends from the piston 71 and has a post 73 secured in its forward end supporting a diamond or other truing tool 74. The piston 71 is actuated by the hydraulic medium which enters same through inlet port 75 from a conduit 76. The other end of the cylinder 70 has a port 77 coupled with a conduit 78. The medium is directed into the conduit 78 by the main valve 30 from a conduit 79 extending from the pressure line 23. The discharge from the conduit 76 is likewise directed by the valve 30 to a conduit 80 for return to the sump or tank 20.

To determine whether one or more work pieces are to be finished between the retruing or redressing operations on the face of the grinding wheel, the following mechanism is employed. The work head slide 40 is provided on its rear face, as shown in Figure 2, with a T shaped slot 81 in which is adjustably mounted a dog 82 having an inclined face 83 for engagement with roller 84 of plunger 85. The plunger 85 is vertically, shiftably mounted in a housing or casing 86, secured to the rear wall of the bed 10. A lever 87, pivotally mounted at 88 to the wall of the casing 86 having a tongue 89 extending therefrom, is received within a slot 90 formed intermediate the ends of the plunger 85. A crank 91 extends from the pivot shaft 88 for rocking movement therewith, and has pivoted thereto, at 92, a pawl 93. The lever 87 is limited in its upward movement in one direction by an adjustable abutment stop 94, and at its other end contacts a spring pressed plunger 95 for returning the lever to its normal position together with the plunger 85. The pawl 93 overlies a ratchet plate 96 formed integral with a sleeve 97 loosely mounted on pivot shaft 88. Secured for movement with the ratchet plate 96 and sleeve 97 is a cam plate 98 having extending from its periphery a lug 99. A spring 100 has one end secured to the pawl 93 and the other end with a fixed part of the mechanism or housing 86, and maintains contact between the point of the pawl and the teeth of the ratchet. While but a single projecting point 99 has been illustrated on the plate 98, it is to be understood that any number of said points may be provided.

Each stroke of the work head 13 causes, through the inner engagement of cam face 83 with roller 84, a depression of the plunger 85 and a rocking of the lever 87 and arm 91 about the pivot shaft 88. Depending on the adjustment of the adjustable stop 94 and consequently the movement of the lever 87, the pawl 93, through the rocking of the arm 91, will pick up one or more of the ratchet teeth

on plate 96 and advance the cam plate 98 correspondingly. This intermittent rotation of the cam plate 98 brings the projection or lug 99 thereon, into engagement with, for depressing a plunger 101 to close a switch 102 carried by the housing or casing 86. As shown diagrammatically in Figure 9, this switch 102 is coupled with a solenoid 103 through electric wires 104 and 105 with the main electrical leads 106 and 107. As shown in Figure 5, the solenoid 103 is connected by a strap 108 with a valve shift lever 109, pivoted at 110 in a housing 86. This housing 86 encloses the main valve 30 to which the valve shift arm 109 is connected for movement thereby. This shifting of the valve 30, as seen in Figure 9, through the solenoid 103 will be to the right, thereby cutting off the flow of the discharge medium through the conduit 49 and stopping further actuation of the work head 43. At the same time the medium being discharged through valve 26 and conduit 29 will pass through a conduit 112 instead of through conduit 31A. The conduit 112 is provided with a choke or needle valve 112a to restrict the flow therethrough, and cause a corresponding slow movement of the wheel head and wheel past the diamond. It will be appreciated that the movement of the wheel head 13 must necessarily be extended to permit the entire face of the wheel to pass across the point of the now stationary diamond or truing tool. To this end the dog 38 is provided with a solenoid 114, from which the wires 115 and 116 extend, being broken by a switch 117. The switch 117, as shown diagrammatically in Figure 9 and structurally in Figure 5, comprises a yieldable mounted depressible plunger 118, cooperating with a cam face 119 formed on the upper end of the valve shift lever 109. This closing of the switch 117 establishes an electrical circuit including the solenoid 114, whereby the dog 38 is raised out of the path of the shift lever 33 so that the wheel head 13 must travel until the dog 120 of the wheel head engages said lever to effect a reversal of the valve, thereby extending the stroke of the wheel head 13 to pass the entire active surface of the grinding wheel 16 across the point of the diamond or other truing tool 74.

Means may also be provided to permit the grinding wheel to make a single pass or a plurality of passes across the truing tool before the said truing tool is retracted, and the normal stroke of the wheel head 13 established to again continue the grinding operation. To this end a T shaped slot 121 is formed in the rear face of the wheel head 13 for an adjustable dog 122, which similar to the dog 82, has an inclined face 123 for engagement with and depression of a plunger 124. This plunger 124 is identical in structure with the plunger 85 for intermittently

rocking or swinging a crank 125 to actuate a pawl 126 for intermittently rotating a ratchet plate 127. The ratchet plate 127 has, similar to plate 96 extending therefrom a sleeve 128, and is connected with for movement thereby a cam plate 129. This cam plate 129 is provided with one or more projections 130 to depress a plunger 131 to close a switch 132. The switch 132 is electrically connected through lines 133 and 134 with a solenoid 135 having its movable core pivotally connected to the other end of link 108 for reversely shifting the valve shifter lever 109 and correspondingly shifting the main valve 30. At this time the cam face 119 is removed from the plunger 118, thereby opening the switch 117 to break the electric circuit which includes the solenoid 114, permitting the dog 38 under influence of spring 38a to return to its normal position.

The operation of the device is as follows: assuming a work piece to have been just completed and, through the size control device, effected a movement of the work head 43 to the rear or away from the wheel head. Assuming further the parts within casing 86 are in the position shown in Figure 5. The retracting movement of the work head 43, will, through the dog 82, depress plunger 85 to advance the cam plate 98 for closing switch 102. This switch 102 completes the electrical circuit including the solenoid 103 to shift the main valve 30 to the position for stopping further movement of the work head 43 and locking same in this position. At this time the hydraulic medium passes through the conduit 76 to shift the piston 71 for positioning the diamond or other truing tool in the line of movement of the active face of the grinding wheel 16. At the time of shifting of the main valve 30, the valve shifter lever 109 closed the switch 117 completing an electrical circuit which included the solenoid 114 to raise the dog 38 out of the path of movement of the lever 33. This permits the wheel head 13 to have an extended stroke so that the entire surface of the grinding wheel 16 passes the said diamond or truing tool 74. The wheel head 13 reciprocates the full stroke permitted by the dogs 39 and 120, and each time the dog 122 on the rear of the said wheel head depresses the plunger 124 for advancing the cam plate 129, and as soon as the cam point 130 thereon engages and depresses plunger 131, the switch 132 is closed, completing an electrical circuit which includes the solenoid 135 and reversely shifts the main valve 30. The number of passes of the wheel head 13 and grinding wheel 16 across the diamond or truing tool is determined by the number of cam points projecting from the cam plate 129, or by the setting of an adjustable stop associated therewith which is similar in construction and function to the stop 94.

As soon as the main valve 30 has been actuated to its normal operating position, the work head 43 again is set in motion simultaneously with the reverse actuation of piston 71 and retraction of diamond or truing tool 74. The normal cycle of the machine then continues until the plunger 85 has again been depressed to the necessary or desired number of times for again retruing or resurfacing the active surface of the wheel 16. The shifting of the valve 30 and lever 109 opened the switch 117, thereby breaking the electrical circuit which included the solenoid 114, permitting the dog 38 under the influence of its spring to descend into the path of the lever 33 to shift the said lever at each end of the short normal grinding stroke.

What is claimed is:

1. In a grinding machine the combination of a bed, a grinding wheel support carried thereby and reciprocable longitudinally thereof, a work support carried by the bed and reciprocable longitudinally thereof toward and from the grinding wheel support, a grinding wheel rotatably carried by the grinding wheel support, means reciprocating the grinding wheel support through a short normal grinding stroke, means reciprocating the work support through a normal work receiving and ejecting stroke, means for interrupting the movement of the work support, means for extending the stroke of the grinding wheel support, and means carried by the work support for resurfacing the grinding wheel at the time the movement of the work head is stopped and the movement of the grinding wheel support is extended.

2. In a grinding machine the combination of a bed, a pair of slides supported by the bed and movable toward and from one another, hydraulic means for actuating the slides, one of the slides rotatably supporting a grinding wheel, the other slide rotatably supporting a work piece to be operated upon by the grinding wheel, means for stopping one of the slides at a predetermined point, and means carried by said slide for resurfacing the active face of the grinding wheel.

3. In a grinding machine the combination of a bed, a pair of slides carried thereby and reciprocable longitudinally thereof, means on one of the slides for rotatably supporting a grinding wheel, means on the other slide for rotatably supporting a work piece to be operated upon by the grinding wheel, means for actuating the slides, means carried by the work slide for resurfacing the active face of the grinding wheel, and means for stopping the work slide while permitting a continued movement of the wheel slide during the resurfacing operation.

4. In a grinding machine the combination of a support, a grinding wheel head carried thereby and reciprocable longitudinally thereof, a grinding wheel rotatably mounted

in the wheel head, a work head carried by the support and longitudinally reciprocable thereof, a trueing tool carried by the work head having an operative and an inoperative position, hydraulic means for effecting the reciprocation of the work head and wheel head, and means for simultaneously stopping the movement of one of the heads and actuating the trueing tool to its operative position.

5. In a grinding machine the combination with a bed or support having formed thereon a pair of guide ways, a wheel head rotatably carrying a grinding wheel and supported by one of the ways for movement longitudinally of the bed, a work head supported by the other way for movement longitudinally of the bed toward and from the grinding wheel, an hydraulic circuit for actuating the wheel head and work head, a main valve in the circuit, supplemental reversing valves in the circuit one for the wheel head and one for the work head each reversing the movement of its respective head, and means for shifting the main valve controlled by the said heads for stopping the movement of one of them while permitting the movement of the other.

6. In a grinding machine the combination with a bed or support having formed thereon a pair of guide ways, a wheel head rotatably carrying a grinding wheel and supported by one of the ways for movement longitudinally of the bed, a work head supported by the other way for movement longitudinally of the bed toward and from the grinding wheel, an hydraulic circuit for actuating the wheel head and work head, a main valve in the circuit, supplemental reversing valves in the circuit one for the wheel head and one for the work head each reversing the movement of its respective head, means for shifting the main valve controlled by the said heads for stopping the movement of one of them while permitting the movement of the other, and means for redressing the active surface of the grinding wheel at the time one of the said heads is held stationary.

7. In a device of the class described the combination of a bed, a pair of slides carried thereby and reciprocable longitudinally thereof toward and from one another, one of said slides supporting a rotating grinding wheel and the other slide supporting a retrueing tool for operation on the active face of the grinding wheel, hydraulic means for actuating the slides, hydraulic means for adjusting the retrueing tool from an inoperative to an operative position, said hydraulic means including a valve, and means controlled by the reciprocating movement of the slides for shifting the valve to simultaneously stop the movement of one of the slides and adjust 65 the retrueing tool to the operative position

for retrueing the active face of the grinding wheel.

8. In a device of the class described the combination of a bed, a pair of slides carried thereby and reciprocable longitudinally thereof toward and from one another, one of said slides supporting a rotating grinding wheel and the other slide supporting a retrueing tool for operation on the active face of the grinding wheel, hydraulic means for actuating the slides, hydraulic means for adjusting the retrueing tool from an inoperative to an operative position, said hydraulic means including a valve, means controlled by the reciprocating movement of the slides for shifting the valve to simultaneously stop the movement of one of the slides and adjust the retrueing tool to the operative position for retrueing the active face of the grinding wheel, and means operable by the remaining slide for reversely shifting the valve to retract the retrueing tool and effect the normal reciprocation of the previously stopped slide.

9. In a grinding machine the combination of a bed, a grinding wheel supported by the bed and reciprocable through a normal work grinding stroke relative thereto, means for extending the normal stroke of the grinding wheel, a work supporting slide reciprocable longitudinally of the bed to present a work piece in operative association with the grinding wheel, a trueing tool carried by the slide adjustable from a position adjacent the grinding wheel to retrue the active surface thereof to a position remote from the grinding wheel, a piston supporting the trueing tool, a reciprocable hydraulic motor for actuating the slide, hydraulic means for actuating the piston and motor, and means operable by the slide for operating the grinding wheel 100 stroke extending means and for actuating the trueing tool.

10. In a grinding machine the combination of a bed, a pair of slides carried thereby and reciprocable longitudinally thereof toward and from one another, one of the slides rotatably supporting a grinding wheel, the other slide supporting a cylinder, a piston reciprocable through the cylinder, a retrueing tool carried by the piston for retrueing the active face of the grinding wheel when the piston is in its forward position, hydraulic means for reciprocating the slides through a normal working stroke, means for extending the stroke of the grinding wheel slide during the retrueing of the active face of the grinding wheel, a valve controlling the flow of the hydraulic medium and the position of the retrueing tool, and means operable by the slide for simultaneously stopping the movement 120 of one of the slides extending the stroke of the other slide and for actuating piston of the retrueing tool to project same adjacent the active face of the grinding wheel.

11. In a grinding machine the combination 130

of a bed, a grinding wheel slide rotatably supporting a grinding wheel and translatable longitudinally of the bed, a work supporting slide carried by the bed and translatable longitudinally thereof toward and from the grinding wheel to operatively associate the work piece carried thereby with the said grinding wheel, a retruing tool carried by the work slide having a position adjacent the 10 active face of the grinding wheel for retruing same and an inoperative position remote therefrom, a depressible plunger carried by the bed in the path of movement of the work supporting slide, an hydraulic circuit including an hydraulic medium for actuating the slides and for positioning the retruing tool, a valve controlling the flow of the medium, and means operable by the depressible plunger for shifting the valve to control the flow 20 of the hydraulic medium therethrough.

12. In a grinding machine the combination of a bed, a wheel head carried thereby and translatable longitudinally thereof, a work head carried by the bed and translatable longitudinally thereof toward and from the wheel head, a grinding wheel rotatably supported by the wheel head, a retruing tool carried by the work head having a position adjacent the active face of the grinding wheel 30 to retrue same and a position remote therefrom, a piston for actuating the wheel head, a second piston for actuating the work head, a third piston for positioning the retruing tool, an hydraulic medium for actuating the pistons, a conduit for the medium, a valve in the conduit, and electromagnetic means for shifting the valve for controlling the flow of the hydraulic medium through the conduit to simultaneously stop the translation of one of the slides and position the retruing tool adjacent the active face of the grinding wheel while permitting continued translation of the other slide, said means including a depressible plunger operable by the work head, an intermittently rotatable cam operatively connected with the plunger, a circuit breaker adapted to be closed by the cam, and means carried by the cam for determining the number of passes of the work head before the said circuit breaker is closed.

13. In a grinding machine the combination of a bed, a wheel head carried thereby and translatable longitudinally thereof, a work head carried by the bed and translatable longitudinally thereof toward and from the wheel head, a grinding wheel rotatably supported by the wheel head, a retruing tool carried by the work head having a position adjacent the active face of the grinding wheel to retrue same and a position remote therefrom, a piston for actuating the wheel head, a second piston for actuating the work head, a third piston for positioning the retruing tool, an hydraulic medium for actuating the pistons, a conduit for the medium, a valve in the conduit, electromagnetic means for shifting the valve for controlling the flow of the hydraulic medium through the conduit to simultaneously stop the translation of one of the slides and position the retruing tool adjacent the active face of the grinding wheel 60 while permitting continued translation of

the other slide, said means including a depressible plunger operable by the work head, an intermittently rotatable cam operatively connected with the plunger, and a circuit breaker adapted to be closed by the cam.

14. In a grinding machine the combination of a bed, a wheel head carried thereby and translatable longitudinally thereof, a work head carried by the bed and translatable longitudinally thereof toward and from the wheel head, a grinding wheel rotatably supported by the wheel head, a retruing tool carried by the work head having a position adjacent the active face of the grinding wheel to retrue same and a position remote therefrom, a piston for actuating the wheel head, a second piston for actuating the work head, a third piston for positioning the retruing tool, an hydraulic medium for actuating the pistons, a conduit for the medium, a valve in the conduit, electromagnetic means for shifting the valve for controlling the flow of the hydraulic medium through the conduit to simultaneously stop the translation of one of the slides and position the retruing tool adjacent the active face of the grinding wheel while permitting continued translation of the other slide, said means including a depressible plunger operable by the work head, an intermittently rotatable cam operatively connected with the plunger, a circuit breaker adapted to be closed by the cam, and means carried by the cam for determining the number of passes of the work head before the said circuit breaker is closed.

15. In a grinding machine the combination of a bed, a pair of slides carried thereby and translatable longitudinally thereof toward and from one another, a rotating grinding wheel carried by one of the slides, means for rotatably supporting a work piece carried by the other slide, a retruing tool carried by the work supporting slide projectable from a position remote from the active face of the wheel to a position adjacent thereto, automatic means for positioning the retruing tool adjacent the active face of the grinding wheel to retrue same at a predetermined time, and means operable by the work supporting slide for operating the last named means.

16. In a grinding machine the combination of a bed, a pair of slides carried thereby and translatable longitudinally thereof toward and from one another, a rotating grinding wheel carried by one of the slides, means for rotatably supporting a work piece carried by the other slide, a retruing tool carried by the work supporting slide projectable from a position remote from the active face of the wheel to a position adjacent thereto, automatic means for positioning the retruing tool adjacent the active face of the grinding wheel to retrue same at a predetermined time, means operable by the work supporting slide for operating the last named means,

and means operable by the grinding wheel supporting slide for retracting the retrueing tool.

17. In a grinding machine the combination of a bed, a slide carried by the bed rotatably supporting a grinding wheel, means for constantly reciprocating the grinding wheel slide through a normal working stroke, a second slide carried by the bed rotatably supporting a work piece, means for intermittently reciprocating the work supporting slide in cyclic sequence through a normal working stroke to present a work piece in operative association with the grinding wheel and to remove it therefrom, a retrueing tool carried by the work supporting slide having a position adjacent the active face of the grinding wheel and a position remote therefrom, means extending the normal working stroke of one of the slides during the retrueing of the active face of the grinding wheel, and means operable by one of the slides for determining the number of cyclic strokes to be made by the work supporting slide before the retrueing of the active face of the grinding wheel and for positioning the retrueing tool adjacent the face of the grinding wheel and simultaneously operating the means for extending the normal working stroke of one of the slides.
18. In a grinding machine the combination of a bed, a slide carried by the bed rotatably supporting a grinding wheel, means for constantly reciprocating the grinding wheel slide through a normal working stroke, a second slide carried by the bed rotatably supporting a work piece, means for intermittently reciprocating the work supporting slide in cyclic sequence through a normal working stroke to present a work piece in operative association with the grinding wheel and to remove it therefrom, a retrueing tool carried by the work supporting slide having a position adjacent the active face of the grinding wheel and a position remote therefrom, means extending the normal working stroke of one of the slides during the retrueing of the active face of the grinding wheel, means operable by one of the slides for determining the number of cyclic strokes to be made by the work supporting slide before the retrueing of the active face of the grinding wheel and for positioning the retrueing tool adjacent the face of the grinding wheel and simultaneously operating the means for extending the normal working stroke of one of the slides, and means operable by the other slide for determining the number of passes the retrueing tool and grinding wheel make relative one to the other.

19. In a device of the class described the combination of a bed or support, a grinding wheel carried thereby and reciprocable longitudinally thereof, a work piece support

carried by the bed and reciprocable longitudinally thereof toward and from the grinding wheel, means for reciprocating the grinding wheel and work support in a cyclic sequence, means for interrupting the cycle, means for re-surfacing the active surface of the grinding wheel during the interruption, and means for re-establishing the operating cycle.

20. In a grinding machine the combination of a bed, a pair of slides carried thereby and shiftable relative thereto toward and from one another, a grinding wheel carried by one of the slides, a truing tool associated with the other slide, means for actuating said slides at normal working rates, means for shifting the truing tool from a point remote from the grinding wheel to a point in line with the movement of the grinding wheel for retruing the face thereof, and means for stopping the movement of one of the slides and changing the rate of movement of the remaining slide to effect a traverse of the tool and wheel relative to one another at a rate below the normal working rate.

21. In a grinding machine the combination of a bed, a pair of slides carried thereby and shiftable relative thereto toward and from one another, a grinding wheel carried by one of the slides, a truing tool associated with the other slide, means for actuating said slides at normal working rates, means for shifting the truing tool from a point remote from the grinding wheel to a point in line with the movement of the grinding wheel for retruing the face thereof, means for stopping the movement of one of the slides and changing the rate of movement of the remaining slide to effect a traverse of the tool and wheel relative to one another at a rate below the normal working rate, and means carried by the bed and slides for energizing the foregoing means.

22. In a grinding machine the combination of a bed, a pair of slides carried thereby and shiftable relative thereto toward and from one another, a grinding wheel carried by one of the slides, a truing tool associated with the other slide, means for actuating said slides at normal working rates, means for shifting the truing tool from a point remote from the grinding wheel to a point in line with the movement of the grinding wheel for retruing the face thereof, and means for stopping the movement of one of the slides and changing the rate of movement of the remaining slide to effect a traverse of the tool and wheel relative to one another at a rate below the normal working rate, said means including a valve for controlling an hydraulic circuit associated with the shiftable parts, electro-magnetic means for shifting the valve, and means carried by the slide for energizing the electro-magnetic means to effect a movement of the valve.

23. In a grinding machine the combination of a bed, a pair of slides carried thereby and shiftable relative thereto toward and from one another, a grinding wheel carried by one of the slides, a truing tool associated with the other slide, means for actuating said slides at normal working rates, means for shifting the truing tool from a point remote from the grinding wheel to a point in line with the movement of the grinding wheel for retruing the face thereof, means for stopping the movement of one of the slides and changing the rate of movement of the remaining slide to effect a traverse of the tool and wheel relative to one another at a rate below the normal working rate, said means including a valve for controlling an hydraulic circuit associated with the shiftable parts, electro-magnetic means for shifting the valve, and means carried by the slide for energizing the electro-magnetic means to effect a movement of the valve, and additional means including electro-magnetic means for shifting the valve to return the parts to their normal working positions, and means carried by the slide for energizing the said electro-magnetic means.

In testimony whereof I affix my signature.
FREDERICK S. HAAS.
